CAR DOOR BUMPER

Floyd A. Terwilliger, 1264 Culver Road, Rochester, N.Y.

Filed Oct. 16, 1961, Ser. No. 67,112

Term of patent 14 years

(Cl. D14—6)

FIG. 1 is a plan view of a car door bumper embodying my new design;

FIG. 2 is an end elevation thereof;

FIG. 3 is a side elevation thereof;

FIG. 4 is a sectional view thereof taken along the line 4—4 of FIG. 1 and looking in the direction of the arrows; and

FIG. 5 is a sectional view thereof taken along the line 5—5 of FIG. 1 and looking in the direction of the arrows.

I claim:

The ornamental design for a car door bumper, substantially as shown.
